UNITED STATES PATENT OFFICE.

JOHN PEARSON, OF CHICAGO, ILLINOIS.

CAR ROOF.

Application filed March 21, 1921. Serial No. 453,969.

To all whom it may concern:

Be it known that I, JOHN PEARSON, a citizen of the United States, residing at Chicago, in the county of Cook, State of Illinois, United States of America, having invented certain new and useful Improvements in Car Roofs, do hereby declare that the following is a full, clear, and exact description of the same.

10 My invention relates to metallic car-roofs, and consists in the novel and useful constructions herein described and then pointed out in the appended claims.

15 In the accompanying drawings, which illustrate practical embodiments of the various features of my invention and in which the same reference numerals indicate similar parts in the different figures,

20 Fig. 1 is a top plan view of a portion of a car-roof showing certain features of my invention, some parts being omitted and other being broken away for the purposes of illustration:

25 Fig. 2 is a cross-sectional view on the line 2—2 of Fig. 1 with one of the running-board saddles shown in place on one of the carline-caps and the running-boards thereon;

30 Fig. 3 is a detail sectional view taken at the eaves showing the construction employed with a wood side-plate;

Fig. 4 is a similar view showing the construction employed with an angular metallic side-plate;

35 Fig. 5 is a perspective view of one of the carline-hoods;

Fig. 6 is a side view of a section of the roof with the eaves ends of a pair of panels and an associated carline-hood in elevation;

40 Fig. 7 is a detail view of the end of a carline with the opposite eaves-strips;

Fig. 8 is a detail perspective view of the end of a carline with its eaves-shield;

Fig. 9 is a side view of one of the ridge-caps;

45 Fig. 10 is a detail sectional view on the line 10—10 of Fig. 2, omitting the parts above the cap-plate;

50 Fig. 11 is a detail sectional view at the ridge showing the arrangement of parts at one of the carlines with a running-board splice-saddle;

Fig. 12 is a perspective view of the inner end of one of the ridge-cover sections;

Fig. 13 is a top-plan detail view of the central portion of one of the carline-caps; 55

Fig. 14 is a cross-sectional view of the same with its parts shown in perspective;

Fig. 15 is a top-plan view, partly in horizontal section, showing one of the cap-plates and the parts below the same at the ridge; 60

Fig. 16 is a sectional view on the line 16—16 in Fig. 15;

Fig. 17 is a detail end view of one of the carline-arms of cap-plate showing the seat for a bolt for a running-board splice-saddle, 65

Fig. 18 is an end view showing an end running-board saddle;

Fig. 19 is a central cross-sectional view of the same; 70

Figs. 20 and 21 are respectively top and face views of an end ridge-shield;

Fig. 22 is a top plan view of the running-boards and one of the intermediate saddles;

Fig. 23 is a vertical sectional view on the line 23—23 in Fig. 22; 75

Fig. 24 is a similar view on the line 24—24 in Fig. 23;

Figs. 25, 26 and 27 are, respectively, top, side and perspective views of one of the 80 running-board brackets.

In the drawings the reference numeral 1 designates the ridge-pole, 2 the side-plates, 3 the side-sheathing, 4 the longitudinal wooden purlines, and 5 the roof-boards extending from the ridge-pole to the side-plates 85 and resting also upon the intermediate purlines; the ridge-pole is rabbeted at each side to form seats for the inner ends of the roof-boards, with its central portion extending above these boards and oppositely inclined

90 from its center to conform to the pitch of the roof, as shown in Fig. 16. Extending transversely of the roof at suitable intervals are the metal carlines which in the present invention are in the shape of I-beams having upper and lower flanges 6 and 7 and connecting webs 8, the carlines extending across the width of the car and resting upon the ridge-pole and side-plates. The carlines are 95

stepped into cross-grooves or mortises 9 in the upper portion of the ridge-pole where their lower flanges are secured in place by bolts 10, and they are connected to the side-plates in any suitable manner; when wooden 100

side-plates are used the carlines are attached 105

to them by means of angular metallic brackets 11 which are bolted to the inner faces of the plates and riveted to the lower flanges of the carlines as shown at 12 and 13 respectively in Fig. 3; when metal side-plates are used the lower flanges of the carlines are riveted to their side-angles as shown at 13 in Fig. 4. The purlines are bolted to the under sides of the lower flanges of the carlines as at 14 in Fig. 10 so that the carlines carry the purlines. The flanges of the carlines are substantially straight from end to center so that the width of the carlines is approximately uniform throughout their length, the lower flange being somewhat wider than the upper flange, and the webs are of uniform height so that the top flanges extend a uniform distance above the ridge-pole, and the under faces of the lower flanges are flush with the under sides of the boards 5. A pair of wood strips 15 is arranged upon the lower flange of each carline on opposite sides of its web; each strip may extend in one piece or in sections from side to side 25 of the car, and in either case they fill the cross-grooves in the ridge-pole so that the upper faces of these parts are flush as shown in Fig. 16. The outer ends of the carline-strips 15 abut against wood strips 16 which 30 extend longitudinally at the eaves between the webs of adjacent carlines and are rabbed to receive their lower flanges as shown in Fig. 7. The carline-strips 15 and the eaves-strips 16 are of substantially the same 35 thickness and are thicker than the roof-boards so that they extend above these boards and with the central portion of the ridge-pole form flush bases to support the metal roof-sheets or panels uniformly at their 40 edges and above the plane of the roof-boards. The strips 15 are pierced to receive the bolt-heads 10 and 14; when metal side-plates are employed the strips 16 are countersunk to receive the heads of the bolts by which they 45 are secured in place, and when wood side-plates are used the strips 16 are nailed to them, their ends being pierced for the rivets 13.

At the eaves at each carline a metal shield 50 is secured to close the joints between the flange 6 and the car sides, between adjacent eaves-strips 16 and between adjacent roof panels; this eaves-shield is angular being composed of a vertical skirt 17 which may be 55 nailed to the adjacent strips 16, and a horizontal ledge 18 which projects into an open-end slot 19 cut in the end of the carline-web and lies in a shallow routing cut in the top of adjacent eaves-strips 16 under the adjacent roof-panels.

The metal roof-panels 20 rest on the bases formed by the upper surfaces of the strips 15 and 16 and of the ridge-pole; each panel is substantially rectangular in shape, extends 65 between adjacent carlines from the ridge-

pole outward to the eaves, and is provided with upturned side-flanges 21, an upturned inner or ridge-flange 22, and a downturned eaves-flange 23 fastened to the outer face of the corresponding eaves-strip 16 and having 70 an inner return-bead 24 to stiffen its edge. The outer corners of adjacent panels overlie the ledge 18 of an eaves-shield and the gap between the ends of their eaves-flanges 23 is closed by its skirt 17 as shown in Fig. 75 6. The side-flanges of the panels lie under the top flanges of the carlines, with sufficient clearance between the parts to form a flexible joint to allow play of the panels along their length under any strains or twisting action 80 of the car-body. The inner corners of the flanges 21 and 22 are formed with vertical crimps 25 to prevent distorting or breaking the metal when the flanges are pressed up, and the outer end of each side-flange 21 is 85 cut away at its top at 26 for a purpose to be described. The panels being above the plane of the roof-boards 5 clear the latter; with light gauge panels the roof-boards may fill the spaces between the carlines, but with 90 heavy gauge panels only one or two boards need be used between the carlines, as in either case they prevent the panels from bending or sagging down upon the purlines.

The carline-caps are formed of sheet metal 95 of inverted trough-shaped in cross-section, each consisting of an upper horizontal top 27 of sufficient width to overlap the carline-flange 6, straight sides 28 of sufficient depth to form a skirt reaching to the panels, and 100 inwardly directed flanges 29 bearing on adjacent panels; they extend from the ridge-pole to the eaves, and each is provided with opposite inwardly projecting ribs 30 in its sides 28 which engage the under faces of the 105 top flange 6 of the carline. These ribs are formed by inwardly bending or swaging the material of the sides at a sufficient distance below the top to provide an intervening passage or channel to snugly receive the 110 flange, and are at the center of the sides, leaving the ends thereof plain, extending along the center of the sides 28 a sufficient distance to firmly lock the caps on the carlines. After the roof-panels are assembled 115 upon their supporting bases between the carlines, the carline-caps are slipped into place on the carlines with their ribs 30 under the carline flanges 6, each being slid along the length of the associated carline beginning at 120 its outer end from the eaves to the ridge-pole, and its sides 28 enclose the flanges 21 of the adjacent panels; when the cap is in position it is held against vertical displacement by its ribs 30, and its lateral flanges 29 125 hold the associated panels down on their bases, these parts thus being interlocked together to hold the panels and caps in place and provide a weather-proof joint, but leaving sufficient clearance between the flanges 130

21 and the carlines and caps to provide a flexible joint to permit the panels to move under strains or twisting actions of the car and so prevent the buckling of their bodies 5 or the fracture of their joints.

Each end of the carlines is provided with an end-hood comprising a vertical body 31 and an angular dome consisting of a top 32 and straight sides 33 which fit over the ends 10 of a carline-cap and its associated carline. When the hood is assembled in place its top 32 rests on the outer end of the top 27 of a carline-cap, its sides 33 fit snugly against the outer faces of the sides 28 of the cap, 15 and its body 31 extends over the ends of the carline and its associated cap and down over the eaves-flanges 23 of adjacent panels. The hoods are of malleable metal, and each is secured in position by means of a U-bolt 34 having its neck located in a hole 35 in the 20 web of the carline and its ends passing through holes 36 in the hood-body and screw-threaded to receive the retaining nuts 37, the cut-aways 26 in the side-flanges 21 of the 25 panels clearing the bolts, as shown in Fig. 3. The lower portion of the body is provided with lateral wings 38 bearing against the eaves-flanges 23 of adjacent panels, and each wing has an angular ear 39 at its top which 30 projects inwardly over a panel in line with the lower ends of the sides 33, the wings and ears forming extended bearings for the hoods on the shields and panels. The body of the hood is formed with outwardly curved 35 or bowed vertical channels 40 in its inner face to provide a weep-passage to carry off any water that may pass beneath the hood.

I also provide a sectional metallic ridge-cover, each section being located between a 40 pair of adjacent carlines and extending longitudinally of the ridge-pole and over the upturned ridge-flanges 22 of an opposite pair of roof-panels upon which its opposite sides rest. Each section of the ridge-cover 45 is inverted trough-shape in cross-section comprising an oppositely inclined top 41 and downturned sides 42 having lateral inturned flanges 43 adapted to overlie and rest upon the upper faces of opposite panels 50 20 with the ridge-flanges 22 thereof in the trough provided by the sides and top. At each end of a section its top and sides are provided respectively with wings 44 and 45, the latter being laterally bent and lying 55 either inside or outside of the sides 28 of opposite carline-caps to protect the opening or space between these parts, and the former being upwardly and inwardly bent to form shoulders and overlie the top flange 3 of the 60 carline between the inner ends of the tops 27 of the opposite carline-caps.

A sheet-metal ridge-cap is preferably placed over the adjacent ends of each group of carline-caps and ridge-covers where they 65 meet at the ridge, each such cap comprising

a top 46 and sides 47, of inverted trough-shape in cross-section and sloping downwardly from its center toward its ends to conform to the pitch of the carline on which it rests, the sides being cut-away to form 70 arches as at 48 to straddle the inner ends of the opposite sections of the ridge-cover, as shown in Fig. 9. The ends of the ridge-cap overlie the inner ends of opposite carline-caps and its top 46 extends across and covers 75 the gap between these ends and also the gap between the adjacent ends of the ridge-cover sections, and as the tops of these sections are below the top of the carline-webs 6 the arches 48 in the sides 47 terminate short of 80 the top of these sides to leave a depending flange 49 on each side to embrace the angular wing 44 of the adjacent ridge-cover section.

A cap-plate is bolted to each carline and overlies the ridge-cap to hold the parts in 85 place, and also provides a base for a running-board saddle or support. The cap-plates are of malleable metal, and each is composed of a body 50 and four lateral arms arranged in opposite pairs 51 and 52, respectively, having depending skirts 53 and 54, respectively, to form inverted troughs. The arms 51 cover the ends of the ridge-cap and the inner ends of the carline-caps, being oppositely inclined to fit the pitch of the 90 carlines, and the arms 52 cover the adjacent ends of the ridge-cover sections and are offset below the plane of the top 50 corresponding to the distance of these sections below the carline-web 6 to provide shoulders 100 55 corresponding to and bracing the flanges 49 of the ridge-cap for the wings 44 of the ridge-sections. In assembling the parts the carline-caps and the ridge-cover sections are placed in position, and the ridge-caps are 105 placed in position over their adjacent ends, and the cap-plates are placed over these parts and bolted in place by the through-bolts 56 having their heads countersunk in the ridge-pole to rest against the lower carline-flanges 110 7 and their shanks passing through both flanges of the carlines and through the ridge-caps and the cap-plates to receive the nuts 57, thus providing a solid all-metal connection between the bolt-head and nut. The 115 cap-plates provide an efficient cover and lock, and each has a strengthening rib 58.

A running-board saddle is mounted at each end of the roof and on each of the cap-plates, these saddles differing in construction according to differences of location with respect to different portions of the running-boards. The end-saddles are shown in Figs. 18 to 21, each formed of a wooden cleat 59 angular in cross-section and having a 120 straight upper edge to which the outer ends of the running-boards 60 are secured. The underside of the horizontal portion or ledge 61 is inclined in opposite directions from the ridge to fit the pitch of the roof and rest 125 130

upon the end panels 20 which are here backed by the end-facias 62 overlying the end-sheathing 63 fastened to the end-plates 64, and by fit-strips 65 which extend from 5 the ridge to the eaves and rest upon the end roof-boards 5, the outer sides of the panels 20 having flanges 200 turned down over the facias as shown in Fig. 19; the underside of the ledge 21 is also gained or 10 grooved at 66 to straddle the end of the outer section of the ridge-cover 41. The skirt 67 of the saddle 59 extends down over the upper edges of the end-facias 62, and is fastened to the end-plates 64 by the bolts 68. 15 A malleable ridge-shield 69 lies between the facias and saddle and in line with the ridge-pole, being rectangular in outline and having its top edge oppositely inclined in both directions from its center to conform to the 20 cross-sectional contour of the top 41 of the ridge-cover into which it fits. The shield is provided on its rear face with a shelf 70 which also is oppositely inclined in both directions from its center to support it upon 25 the facias, and with holes 71 for suitable fastening devices passing through the flanges 200 and entering the facias. The outer end of the top 41 of the ridge-cover is extended and split longitudinally so that its opposite 30 leaves fold down over the shield 69 with their inner edges overlapping as at 410 and fastened as at 411 to the facias.

The splice-saddles, used at the butting ends of the sections of the running-boards 35 60, are shown in Figs. 11 and 16. Each consists of a wooden cleat 72 which is bolted to the cap-plate by bolts 73, whose heads are located in seats provided by arches 74 formed in the ends of the carline-arms 51 of 40 the cap-plate, the top wall of each arch having a bolt-opening, preferably in the form of an open-end slot 75 to allow the shank of the bolt to be passed laterally into it to seat its head under the arch after the 45 cap-plate is in place. The undersides of the saddles are suitably routed out to fit over the cap-plates and their bolt-nuts 57, and are inclined to fit the pitch of the carlines upon which they are carried, and the running-boards 60 are secured to them by any 50 suitable means. As both the end-saddles and splice-saddles support ends of the running-board sections, they are made of wood so that the ends of the boards may be easily 55 fastened to them by nailing.

The intermediate saddles, used at points between the splice-saddles and also between these latter and the end-saddles, are of metallic construction throughout being shown 60 in Figs. 22 to 27. Each cap-plate used in such intermediate position is provided with a vertical skeleton web 76, preferably cast integral therewith, and each of its ends having a horizontal ledge 77 terminating at its 65 outer end in a widened shelf 78, the web be- ing cut-away or recessed at its center to countersink the heads of the attaching bolts below the ledge, and the inner ends of the ledges being spaced apart as shown. Brackets are removably mounted on the ledges to 70 space the adjacent running-boards apart and also to lock them to the saddles. In the form shown the brackets are of cast metal, and each has a top or body 79 with an opposite pair of depending legs 80 which are 75 spaced apart a distance sufficient to form an open loop to embrace the ledge 77 and have inwardly directed toes 81 at their lower ends to engage the underside of the ledge, so that the brackets may be easily assembled in 80 place by merely passing their loops over the inner ends of the ledges and then sliding them along the ledges to the desired position thereon, when their toes will hold them against upward displacement. The legs are 85 of sufficient width to space apart the adjacent boards 60, and are longer than the thickness of these boards. Near their lower ends the legs carry laterally projecting ears 90 arranged in opposite pairs 82 and 83, respectively, one at each corner, extending horizontally away from the legs and having their upper faces in the horizontal plane of the associated ledge and shelf when the parts are assembled to underlie and support 95 the adjacent edges of the boards 60 resting thereon. At its upper end on each side the bracket carries a laterally projecting flange 100 84 in a plane above and parallel with its ears, thereby providing an intermediate flange on each side of the bracket, the distance between each flange and the ears below it being preferably somewhat less than the thickness of the boards 60, so that the latter are routed out on their top surfaces to 105 permit their edges to pass into the spaces between the ears and flanges. In assembling the parts, a bracket is positioned on each ledge 77, with sufficient space between them to permit the middle board 60 to be laid 110 upon the inner ends of the ledges, when the brackets are slid inwardly toward the center board to engage its opposite edges between the ears 82 and one of the flanges; the outer boards 60 are then positioned with their 115 inner edges between the ears 83 and the other flange of the brackets, and bolts 85 are passed through them and through the shelves 78 to secure the parts in permanent relation. The brackets uniformly space the 120 boards apart and interlock them with the saddles; their ears may be omitted, as in either case the toes and flanges interlock the parts and the flanges hold the boards in position on the ledges and prevent their 125 warping. When provided with ears the brackets may be used to splice adjacent ends of the running-boards as the separation of their ears along the length of the boards enables them to underlie and support adj- 130

cent ends while their flanges overlie and hold them in place, as shown at the right hand of Fig. 22; while the lower supporting ears may be made narrow, it is preferable 5 to widen them out in the form shown as then they afford increased bearing surfaces for the boards, which is an advantage especially where the brackets splice the ends of the boards.

10 I claim:

1. In a car-roof, side-plates, a ridge-pole having spaced mortises, a plurality of carlines extending between the side-plates and having flanges stepped into the mortises,

15 roof-panels between adjacent carlines, and bases for the panels comprising portions of the pole intermediate the mortises, strips on the carline-flanges flush with the intermediate portions of the pole, and eaves-strips 20 between the outer ends of the adjacent carlines flush with the carline-strips.

2. In a car-roof, side-plates, a ridge-pole having rabbeted sides and spaced mortises, a plurality of carlines extending between the 25 side-plates and having flanges stepped into the mortises, roof-boards extending from the rabbeted sides of the pole to the side-plates, roof-panels between adjacent carlines, and bases for the panels above the plane of the 30 roof-boards comprising the central portions of the pole, strips on the carline-flanges flush with the central portion of the pole, and eaves-strips between the outer ends of adjacent carlines flush with the carline-strips.

35 3. In a car-roof, side-plates, a ridge-pole having rabbeted sides and spaced mortises in its central portion, a plurality of I-shape carlines extending between the side-plates and having their lower flanges stepped into 40 the mortises and their top flanges above the pole, roof-boards extending from the rabbeted sides of the pole to the side-plates with their under sides flush with the under faces of said lower flanges, eaves-strips intermediate 45 the webs of adjacent carlines and rabbeted over their lower flanges, strips on said lower flanges intermediate the eaves-strips and central portion of the pole and flush therewith to form panel-bases, roof-panels 50 on said bases, and caps on the top flanges of the carlines covering the joints between adjacent roof-panels.

4. In a car-roof, a series of car lines, eaves-strips intermediate the carlines, roof- 55 panels on the strips, and an eaves-shield at the end of each carline between the panels and strips closing gaps between adjacent strips and adjacent panels.

5. In a car-roof, a carline having a web 60 provided with an open-end slot, roof-panels adjacent the web, and an eaves-shield in the slot and under the joint between adjacent panels.

6. In a car-roof, a series of carlines having 65 webs, the end of each web being provided

with an open-end slot, eaves-strips intermediate adjacent webs, roof-panels on the strips having eaves-flanges, and an eaves-shield comprising a ledge in the slot resting on adjacent strips below the panels, and a 70 skirt extending down over the edges of adjacent strips and under the eaves-flanges of adjacent panels.

7. In a car-roof, a series of carlines, each having a web provided with a hole near its 75 outer end, panels intermediate the carlines, caps on the carlines, hoods on the ends of the carlines covering the ends of the caps, each hood having a front, top and straight sides, and a U-bolt in the hole of the carline 80 passing through the hood-front.

8. In a car-roof, a carline, panels adjacent the carline, a cap on the carline having straight sides, a hood on the end of the carline and comprising a vertical body provided 85 with a weep-passage in its inner face and a dome having straight sides covering the sides of the cap, and a U-bolt passing through the carline and front of the hood-body.

9. In a car-roof, a series of panels, a series 90 of carline-caps extending from the ridge to the eaves covering the joints between the panels, a ridge-cover for opposite panels composed of trough-shape sections abutting against adjacent caps, and sheet-metal ridge- 95 caps each comprising a top and sides sloping from its center toward its ends to enclose the ends of opposite carline-caps, and the sides being arched to straddle the ends of opposite ridge-sections.

10. In a car-roof, a series of panels, a series 100 of carlines, carline-caps, a ridge-cover composed of trough-shape sections, each section having lateral wings and upturned wings with extensions resting on the carlines, and sheet-metal ridge-caps each having a top closing the joints between opposite carline-caps and opposite extensions of the upturned wings, and sides arched at their center to straddle the ridge-sections, the 110 sides of the arches covering the lateral wings and the tops of the arches covering the upturned wings of the ridge-sections.

11. In a car-roof, a metal carline, a sectional carline-cap, a sectional ridge-cover, a 115 sheet-metal ridge-cap covering the joints between the sections of the carline-cap and ridge-cover, a metal cap-plate covering the ridge-cap, and a through-bolt having its head bearing on the carline with its shank 120 passing through the ridge-cap and cap-plate and its nut on the top of the latter providing an all-metal connection between the bolt head and nut.

12. In a car-roof, a ridge shield having a 125 shelf on its inner face resting on the car-end, means to fasten the shield in place, an angular wooden cleat straddling the shield and resting on the roof, the upper edge of the cleat being flat to seat the outer ends of the 130

running-boards, and its skirt extending down over the shield and car-end, and means to fasten the skirt in place.

13. In a car-roof, a ridge-cover, a ridge-shield under the end of the cover having a shelf on its inner face resting on the car-end, means to fasten the shield in place, an angular wooden cleat straddling the ridge-cover and resting on the roof, the upper edge of 5 the cleat being flat to seat the outer ends of the running-boards, and its skirt extending down over the shield and car-end, and means to fasten the skirt in place.

14. In a car-roof, a ridge-cover having its 15 top extended beyond the car-end, a ridge-shield under the end of the cover having a shelf on its inner face resting on the car-end, means to fasten the shield in place, the extended top of the ridge-cover being split 20 and its leaves overlapped upon the shield, an angular wooden cleat composed of a horizontal ledge for the running-boards and a vertical skirt, the underside of the ledge straddling the cover and resting on the roof, 25 and the skirt extending down over the shield and car-end, and means to fasten the skirt in place.

15. In a car-roof, a pair of roof-panels having downturned end-flanges, a ridge-cover 30 having its top extended beyond the car-end, a ridge-shield under the cover having a shelf on its inner face resting on the car-end, means to fasten the shield in place over the inner ends of the end-flanges, the 35 extended top of the ridge-cover being split and its leaves overlapped upon the shield, an angular wooden cleat composed of a horizontal ledge for the running-boards and a vertical skirt, the under side of the ledge 40 straddling the cover and resting on the roof-panels, and the skirt extending down over the shield and car-end, and means to fasten the skirt in place.

16. In a car-roof, a metal cap-plate having 45 trough-shaped lateral arms, arches in the ends of the arms having top openings, bolts having their heads in the arches with their shanks projecting through the openings, a wooden cleat above the cap-plate 50 through which the bolts pass to receive their cleat-retaining nuts, and running boards mounted on the cleats.

17. In a car-roof, a metal cap-plate having 55 trough-shaped lateral arms, arches in the ends of the arms having open-end slots in their top-walls, bolts having their heads in the arches with their shanks projecting through the slots, a wooden cleat above the cap-plate through which the bolts pass to 60 receive their cleat-retaining nuts, and running boards mounted on the cleat.

18. In a car-roof, a carline, a metal cap-plate 65 having trough-shaped lateral arms embracing the carline, arches in the ends of the arms having open-end slots in their top-

walls, bolts having their heads in the arches with their shanks projecting through the slots, a wooden cleat resting on the carline and straddling the cap-plate and through which the bolts pass to receive their cleat-retaining nuts, and running boards mounted on the cleat.

19. In a car-roof, a cap-plate having a vertical web, a horizontal ledge at each end of the web, brackets slidably mounted on 70 the ledges, means to retain the brackets against vertical displacement, lateral flanges on the brackets, and running-boards on the ledges with their edges under the flanges.

20. In a car-roof, a metal cap-plate having 80 a vertical web, a horizontal ledge at each end of the web, brackets composed of a pair of connected legs slidably mounted on the ledges and having inner toes to retain them against vertical displacement, lateral flanges on the brackets, and running-boards on the ledges with their edges under the flanges.

21. In a car-roof, a cap-plate having a vertical web, a horizontal ledge at each end 90 of the web, brackets slidably mounted on the ledges, means to retain the brackets against vertical displacement, upper and lower lateral projections on the brackets, and running-boards on the ledges with their edges 95 between the projections.

22. In a car-roof, a running-board saddle having a horizontal ledge, outer and intermediate boards on the ledge, and combined spacing and retaining brackets on the ledge 100 between the boards having toes at their lower ends and lateral flanges on their upper ends to interlock with the ledge and boards.

23. In a car-roof, a metal cap-plate having 105 a vertical web provided with a central recess, a horizontal ledge on the web at each side of the recess, brackets composed of a body and a pair of depending legs slidably mounted on the ledges and having inner 110 toes to retain them against vertical displacement, lateral flanges at the upper end of each bracket, and running-boards on the ledges with their edges under the flanges.

24. In a car-roof, a metal cap-plate having 115 a vertical web provided with a central recess, a horizontal ledge on the web at each side of the recess, brackets composed of a body and a pair of depending legs slidably mounted on the ledges and having inner 120 toes to retain them against vertical displacement, lateral ears on the lower ends of the legs arranged in opposite pairs, lateral flanges at the upper end of each bracket parallel with said ears, and running-boards 125 on the ledges with their edges between the flanges and ears.

25. In a car-roof, a metal cap-plate having 130 a vertical web provided with a central recess, a horizontal ledge on the web at each

side of the recess, brackets composed of a body and a pair of depending legs slidably mounted on the ledges and having inner toes to retain them against vertical displacement, lateral ears on the lower ends of the legs arranged in opposite pairs, lateral flanges at the upper end of each bracket parallel with said ears, the ears being of larger area than the flanges, and running-boards on the ledges with their edges between the flanges and ears.

In testimony whereof I affix my signature this 7th day of March, A. D. 1921.

JOHN PEARSON.
